F. JERDONE, JR.
FUEL RESERVE SUPPLY SYSTEM.
APPLICATION FILED APR. 8, 1919.

1,357,986.

Patented Nov. 9, 1920.

UNITED STATES PATENT OFFICE.

FRANCIS JERDONE, JR., OF TOLEDO, OHIO, ASSIGNOR TO INDUSTRIAL RESEARCH CORPORATION, OF TOLEDO, OHIO, A CORPORATION OF DELAWARE.

FUEL-RESERVE-SUPPLY SYSTEM.

1,357,986.

Specification of Letters Patent. Patented Nov. 9, 1920.

Application filed April 8, 1919. Serial No. 288,494.

To all whom it may concern:

Be it known that I, FRANCIS JERDONE, Jr., residing at Toledo, county of Lucas, State of Ohio, have invented certain new and useful Improvements in Fuel-Reserve-Supply Systems, of which I declare the following to be a full, clear, and exact description.

My invention relates to a fuel reserve supply system for self-propelled vehicles, and has for its object to provide simple and inexpensive means by which a reserve supply of fuel may be carried in the main fuel supply tank from which fuel is fed to the engine.

Another object of the invention is to provide a liquid fuel holding receptacle having an outlet passageway with suitable means for automatically closing the passageway when the liquid in the receptacle is reduced to a predetermined amount, said means being movable to open said passageway and arranged to be held in position to prevent the closing of the passageway while the reserve supply of fuel is being consumed and to be automatically released for proper functioning when a supply of liquid greater than said predetermined amount is placed in said receptacle.

Another object of the invention is to provide a liquid holding tank having an outlet passageway with which is connected an aspirator for drawing the liquid from the tank, a valve being provided for automatically closing said passageway when the liquid in the tank is reduced to a predetermined amount, means being provided for holding the valve in open position while said predetermined amount of liquid is being discharged from the tank, said valve being automatically released from said holding means when a new supply of liquid is placed in the tank greater than said predetermined amount.

Another object of the invention is to provide means arranged to be automatically controlled by the rise and fall of liquid in the tank above a predetermined point for opening and closing a passageway leading from the tank with a device for temporarily holding said passageway controlling means in open position, said means being adapted to automatically close said passageway whenever the supply of liquid in the tank is reduced to a predetermined amount.

Another object of the invention is to pro-

vide in combination with an internal combustion engine, and a fuel supply tank connected with the manifold and carburetor of the engine, as is usual in vacuum feed systems, improved means for limiting the amount of fuel to be drawn from the tank, said means requiring the driver of the car, when a predetermined amount of fuel has been used to effect its setting to a position which will permit the reserve supply to be used by the engine, and which will be automatically actuated to release position when a new supply of fuel is placed in the tank greater than said predetermined amount.

Another object of the invention is to provide in combination with the vacuum fuel feed system of an internal combustion engine, improved means for controlling a reserve supply of fuel in the tank, which supply can be used only upon manual operation of the device after a predetermined amount of the fuel has been used and which will not require further manipulation until a new supply of fuel greater than the reserve supply has been placed in the tank and reduced to a predetermined amount as previously arranged for.

To these and other ends the invention comprises certain novel features of construction and arrangement of parts as will be hereinafter more fully described and claimed, it being understood that various modifications in the detailed construction of the device may be made without departing from the spirit of the invention as expressed in the claims.

A structure illustrating one embodiment of my invention is shown in the accompanying drawing forming a part of this specification, in which:

Figure I is a diagrammatic view embodying the invention.

Fig. II is a fragmentary sectional elevation of a fuel tank with my invention applied thereto, the fuel control valve being shown in closed position.

Fig. III is a similar view with the valve shown in open position.

Fig. IV is a sectional plan taken on line IV—IV of Fig. II.

Fig. V is a detailed plan of the upper portion of the valve operating mechanism shown in Fig. II.

Fig. VI is a sectional plan taken on line VI—VI of Fig. II and

110

Fig. VII is a detailed view of a slightly modified form of the invention.

Like reference characters throughout the several views of the drawing indicate corresponding parts.

Heretofore in the construction of fuel reserve supply systems for internal combustion engines, devices have been provided which require the driver, when replenishing the fuel supply, to manipulate some sort of mechanism in order to permit a new supply of fuel to be drawn from the tank. Devices of this kind are objectionable for the reason that they are a tax on the memory of the driver, and at times when he forgets to perform the proper function of setting the device at a predetermined position, the entire fuel supply is consumed by the engine before the driver's attention is called to the fact, thus defeating the main object of the invention.

In the present invention one of the objects is to overcome this objection by providing means which will require manual operation only at the time when all but the reserve supply of fuel has been consumed by the engine, after which the device is automatic in operation until the second supply of fuel has been reduced to a pre-determined amount. In other words, whenever the tank is filled above a pre-determined point, the mechanism for controlling the supply of liquid is automatically moved to release position so that it will automatically prevent the discharge of the liquid from the tank below a pre-determined point.

Referring to the drawing, 10 represents an internal combustion engine such as is used on motor driven vehicles. A vacuum feed tank 11 is connected with the manifold 12 of the engine by means of a conduit 13, and the carburetor 14 of the engine is connected with said vacuum tank by means of a conduit 15, while the main fuel supply tank 16 is connected with said vacuum tank by means of a conduit 17, all as shown in Fig. I. Although in the present instance the means for drawing the fuel from the main supply tank comprises an internal combustion engine, it will be understood that any form of aspirator may be employed to force the liquid out of the supply tank to any desired point or that it may be fed therefrom by gravity.

It will be further understood that while the present invention is designed particularly for controlling the liquid fuel supply for internal combustion engines, that the device may be employed for controlling other kinds of liquids to be used for other purposes as desired.

In the top of the tank 16 I provide an opening 18 which is protected by a cover plate 18', which may be secured upon the tank by any desired means such as by solder-

ing. Projecting into the tank through the cover plate 18' is a tube 19 threaded at its upper end to receive the nut 20 on the underside of said plate and the member 21 on the upper side of said plate as shown in Fig. II, 70 the conduit 17 being connected with the member 21 by means of a reducing coupling 22, as shown at the left of Fig. I. The lower end of the tube 19 which projects to a point adjacent the bottom of the tank is 75 provided with a cap 23 for closing the open end of the tube, the outer face of said cap being tapered as indicated at 24. The cap and tube are provided with a plurality of registering openings 25 through which liquid 80 is adapted to be drawn when a vacuum is created in the gravity feed tank 11 shown in Fig. I, or the liquid may be discharged through the pipe 25' when the valve 26' is in open position. The tapered or conical 85 face 24 of the cap 23 forms a valve seat for the conical shaped valve 26, which is preferably integrally connected with the sleeve 27 slidably mounted on the tube 19. The sleeve 27 is provided at its upper end with 90 a float 28 of any preferred form of construction, it being understood that the float 28, sleeve 27 and valve 26 are free to move up and down in the tank, the position of said parts upon the tube depending upon the 95 height of the liquid in the tank. A lifting mechanism for said float and valve comprises a plate 29 upon the float and a rod 30, which extends through an opening in the plate 29 at a point where it projects laterally 100 from the float, said opening terminating in a slot 31 of less width than the diameter of the rod 30, to prevent displacement of the latter. The rod 30 is provided at its lower end with a nut 32 adapted to engage the 105 plate 29 when the rod is lifted for the purpose of moving the float and valve 26 to uncover the fuel outlet passageways 25 in the bottom of the tube 19. The rod is provided with a laterally projecting pin 33, which is 110 of a less diameter than the width of the slot 31 in the plate 29, and when the rod is in position to cause the pin to register with the slot as shown in Fig. II, the float and plate 29 together with the valve 26 are free to 115 move up and down in the tank without affecting movement of said rod. The upper end of the rod is bent to form a handle 34, the downwardly extending portion 35 of which is provided with a sleeve 36, adapted 120 to engage a projection 37 on the plate 18', as shown in Fig. III, when it is desired to place said rod in position to cause the valve 26 to uncover the openings 25 in the bottom of the tube 19. Coiled around the rod above 125 the plate 18' is a spring 38, the lower end of which is anchored upon said plate by any suitable means such as a screw 39, while the upper end of said spring is connected with said rod in a suitable manner, as by being 130

extended through an opening in the rod as indicated at 40. The spring 38 is tensioned in such a manner as to rotate the rod clockwise when released and a stop 41 is positioned upon the plate 18' for limiting the movement of the rod under the action of the spring, the stop being secured by a screw 42 and positioned so that the rod will rotate through an angle of 90° when moving from the position shown in Fig. III to that shown in Fig. II. The spring is also tensioned longitudinally to effect a quick depression of the rod when released from the holder 37, and serves also to yieldingly hold the sleeve 35 in engagement with the plate 18' when the rod is in normal position.

In the modification shown in Fig. VII, I have provided a holder 43 secured upon the plate 18' in any suitable manner, said holder being provided with a recess 44 adapted to receive the downwardly turned portion 45 of the handle 46 on the upper end of the rod 47. A stop 48 is secured to the plate 18 by means of a screw 49, said stop serving to limit the movement of the rod when turned by the spring 50, the upper end of which is anchored to said plate by a screw 51, while the lower end of said spring is connected with said rod 47 preferably by being extended through an opening therein as indicated at 52, said spring being tensioned sufficiently to rotate the rod from the position shown in Fig. VII, through an angle of 90° into engagement with the stop 48. The spring is also tensioned longitudinally to depress the rod and to prevent rattling of the same when the car is in motion. When the rod is in normal position, the pin 33 is in line with the slot 31 in the plate 29 thus permitting movement of the float and valve up and down, as the liquid rises and falls in the tank. When the liquid in the tank has been reduced to a pre-determined amount, constituting the reserve supply, the discharge passageway 25 will be automatically closed by the valve 26 so that no more liquid can be withdrawn from the tank until the valve is opened. The closing of the valve and the consequent shutting off of the fuel supply to the engine directs the attention of the driver to the fact that the fuel is low, and that only the reserve supply remains in the tank. In this case the position of the float and valve is that shown in Fig. II of the drawing, and before the driver can proceed further, it is necessary that the valve be opened to permit the use of the reserve supply of fuel in the bottom of the tank. This is done by raising the rod 30 by means of the handle 34 and then turning it through an angle of 90° into proper engagement with the holder 37 or the holder 43 as the case may be, and with the handle and rod in this position the float and valve 65 are elevated to the position shown in Fig.

III, where they will temporarily remain to permit the discharge of the reserve supply of fuel through the tube 19 and connections leading to the carburetor of the engine or through the pipe 25' if desired. When the rod is moved from the position shown in Fig. II to the position shown in Fig. III, the pin 33 at the bottom of the rod will be turned to the position indicated by dotted lines in Fig. VI or transversely of the slot 31, and when a new supply of liquid is placed in the receptacle greater than the reserve supply, the float will be raised and the plate 29 will serve to lift the rod through contact with the pin 33. As soon as the rod has been lifted sufficiently to permit the sleeve 36 to clear the holder 37, the spring 38 serves to rotate said rod clockwise until the sleeve comes in contact with the stop 41, at which time the pin 33 is brought into registering relation with the slot 31 in the outer end of the plate 29, and the float is then free to descend and close the valve 26 when all but the reserve supply of fuel has been used from the tank. When the rod is lifted the spring will of course be expanded and when said rod is released by the action of the float, the spring not only serves to rotate said rod as previously stated but also to quickly depress the same until the sleeve 36 comes in contact with the plate 18' whereby the return of the rod to normal position is positively assured whenever it is released by said float.

In the modification shown in Fig. VII, however, when the rod is lifted, the spring 50 instead of being expanded is compressed, and when the down-turned portion 45 of the handle 46 is moved out of the recess 44 of the holder 43, said spring will both rotate and depress said rod until the down-turned portion of the handle engages the plate 18' of the tank 16. By putting sufficient tension upon the springs they will prevent accidental rotation of the rod counter-clockwise from normal position and will prevent the same from rattling when the car is in motion.

It will be understood, of course, that the engine will not stop immediately upon the closing of the valve in the main supply tank, as there will be sufficient fuel in the gravity feed tank and carburetor to supply the engine for a relatively short period of time, after which the driver's attention is called to the fact that the fuel control valve is closed and must be set in open position. When the engine stops for lack of fuel in the carburetor, it must be started by external mechanism and kept going until sufficient fuel is pumped into the gravity feed tank and fed to the carburetor to permit the engine to be run by the explosion of gas in the cylinders. A comparatively few revolutions of the crank shaft will suffice

for this purpose, and this work may be performed by the engine starter, or the engine may be cranked by hand if not provided with a self starter.

5. What I claim as new and desire to secure by Letters Patent is:

1. A liquid holding receptacle having an outlet passageway, and means for controlling said passageway to automatically close the same when the supply of liquid in the receptacle is reduced to a predetermined amount, said means being arranged to be set in position to hold said passageway open to permit the continuance of the discharge of liquid from the receptacle, a new supply of liquid in the receptacle greater than said pre-determined amount being effective to release said means to permit it to again close said passageway when said last mentioned supply of liquid is reduced to the predetermined amount.

2. A liquid holding receptacle having an outlet passageway, means for controlling said passageway to automatically close the same when the supply of liquid in the receptacle is reduced to a predetermined amount, and a holder for supporting said means in open position, said means being automatically released from the holder when a new supply of liquid greater than said predetermined amount is placed in said receptacle.

3. A liquid holding receptacle having an outlet passageway, an aspirator connected with said receptacle adapted to force the liquid through said passageway, and means for automatically closing the passageway when the supply of liquid in the receptacle is reduced to a predetermined amount, said means being movable to open said passageway when closed to permit the continuance of the discharge of liquid from the receptacle, a new supply of liquid in the receptacle greater than said predetermined amount being effective to operate upon said means to place it in position to again automatically close said passageway when said last mentioned supply is reduced to the predetermined amount.

4. A liquid holding receptacle having an outlet passageway, an aspirator connected with said receptacle adapted to force liquid through said passageway, means for controlling said passageway to automatically close the same when the supply of liquid in the receptacle is reduced to a predetermined amount, and a holder for supporting said means in open position, said means being automatically released from the holder when a new supply of liquid greater than said predetermined amount is placed in the receptacle.

5. A liquid holding receptacle having an outlet passageway, a float actuated valve for controlling said passageway to auto-

matically close the same when the supply of liquid in the receptacle is reduced to a predetermined amount, and a holder for supporting said float actuated valve in open position, said valve being automatically released when a new supply of liquid greater than said predetermined amount is placed in said receptacle.

6. A liquid holding receptacle having an outlet passageway, a float controlled valve adapted to automatically close the passageway when the supply of liquid in the receptacle is reduced to a predetermined amount, a member for lifting said float to open said valve, and means for holding said member in position to prevent the closing of the valve, said member being automatically released from said holding means when a new supply of liquid greater than said predetermined amount is placed in said receptacle.

7. A liquid holding receptacle having an outlet passageway, a float actuated valve for controlling said passageway to automatically close the same when the supply of liquid in the receptacle is reduced to a predetermined amount, means for raising said float to open said valve, means cooperating with said last mentioned means to hold the float in raised position, said float raising means being automatically released when a new supply of liquid is placed in the receptacle greater than said predetermined amount, whereby the valve is permitted to return to close position when the new supply of liquid is reduced to the predetermined amount.

8. A liquid holding receptacle having an outlet passageway, a float controlled valve adapted to automatically close said passageway when the supply of liquid in the receptacle is reduced to a predetermined amount, a rod for lifting said float and valve, means for temporarily maintaining said rod in raised position, said rod being automatically moved to release position when a new supply of liquid greater than said predetermined amount is placed in said receptacle, and a spring for returning the rod to normal position when released.

9. A liquid holding receptacle having an outlet passageway, a float controlled valve for closing said passageway when the supply of liquid in the receptacle is reduced to a predetermined amount, a lifter for raising said float to open said passageway, means for temporarily holding said lifter in raised position, said lifter being automatically moved to release position when a new supply of liquid greater than said predetermined amount is placed in said receptacle, and means arranged to yieldingly hold said lifter in normal position when released.

10. A liquid holding receptacle having a tube projecting therein, provided with an opening adjacent its lower end, an aspirator

connected with said tube, a sleeve slidably mounted upon the tube for controlling said opening, a float connected with said sleeve, a lifter connected with said float, a holder for temporarily retaining said lifter in position to prevent the closing of said opening by said sleeve, and a stop upon said lifter adapted to be engaged by said float for moving the lifter to release position when a predetermined amount of liquid is placed in said tank.

11. A liquid holding receptacle provided with a liquid discharge passageway, a valve for controlling said passageway, a float for controlling said valve to automatically close the passageway when the liquid in said receptacle is reduced to a predetermined amount, an adjustable rod movable from normal position to shift the valve to open position, means for engaging said rod to temporarily hold it in adjusted position, said rod being arranged to be automatically released from said holding means when the liquid in the receptacle is increased above said predetermined amount, and means for returning the rod to normal position when released.

12. A liquid holding receptacle provided with a liquid discharge passageway, a valve for controlling said passageway, a float for controlling said valve to automatically close the passageway when the liquid in said receptacle is reduced to a predetermined amount, an adjustable rod movable from normal position to shift the valve to open position, means for engaging said rod to temporarily hold it in adjusted position, and a projection upon the rod arranged to be engaged by the float when the liquid in the receptacle is increased above said predetermined amount whereby the rod is released from said holding means, and means for returning said rod to normal position when released.

13. A liquid holding receptacle provided with a liquid discharge passageway, a valve for controlling said passageway, a float for controlling said valve to automatically close the passageway when the liquid in said receptacle is reduced to a predetermined amount, a rod rotatable in the receptacle and normally in position to permit free movement of the float up and down therein, means by which the raising of said rod is effected by said float, and means by which the rod is held in raised position to hold said valve in open position, said rod being adapted to be actuated by said float to release position when the liquid in the receptacle is increased above said predetermined amount, and means for depressing and rotating said rod back to normal position when released.

14. A liquid holding receptacle provided with a discharge passageway, a valve for

controlling said passageway, a float for controlling said valve to automatically close the passageway when the liquid in said receptacle is reduced to a predetermined amount, a longitudinally movable rod rotatably mounted in said receptacle upon which said float is adapted to travel in its up and down movement, a projection upon the rod normally out of the path of the float, means for holding said rod in an elevated position when moved to place said projection in the path of the float, the projection being engaged by said float when the liquid in said receptacle is increased above said predetermined amount, whereby said rod is moved out of engagement with said holding means, and means for returning the rod to normal position when released.

15. A liquid holding receptacle provided with a liquid discharge passageway, a valve for controlling said passageway, a float for controlling said valve to automatically close the passageway when the liquid in said receptacle is reduced to a predetermined amount, a plate projecting from said float having an aperture there-through communicating with a slot formed in said plate, a rod rotatably mounted in said aperture, the diameter of the rod being greater than the width of said slot, a head upon said rod beneath said plate, a pin projecting laterally from the rod above said plate, the diameter of said pin being less than the width of said slot, said rod being normally in position to cause said pin to register with the slot, whereby movement of the float up and down in the receptacle is permitted without movement of the rod, means by which the rod is lifted and rotated into position to cause said pin to extend transversely of the slot, means for temporarily holding said rod in said elevated position, the plate upon said float engaging said pin when the float is raised above a predetermined point by the liquid in the receptacle whereby said rod is moved to release position, and means for returning the rod to normal position to permit free movement of the float and plate thereon.

16. A liquid holding receptacle provided with a liquid discharge passageway connected with the manifold and carburetor of an internal combustion engine, a valve for controlling said passageway, a float for controlling said valve to automatically close the passageway when the liquid in said receptacle is reduced to a predetermined amount, an adjustable rod movable from normal position to shift the valve to open position, means for engaging said rod to temporarily hold it in adjusted position, said rod being released from said holding means when the liquid in the receptacle is increased above said predetermined amount, and means for returning the rod to normal position when released.

- 6
17. A liquid holding receptacle having an outlet passageway, and manually adjustable means for controlling said passageway to maintain it in open position under certain predetermined conditions and to automatically open and close the same when the liquid in the receptacle rises and falls above and below a predetermined point.
18. A liquid holding receptacle having a tube projecting therein provided with an inlet passageway adjacent its lower end, an aspirator connected with said tube adapted to draw liquid through the tube against the action of gravity, and a float controlled member slidably mounted upon the tube and arranged to automatically open and close said passageway when the liquid in the receptacle rises and falls above and below a predetermined point.
19. A liquid holding receptacle having a tube projecting therein in position to discharge liquid from a point adjacent the bottom of the receptacle through the top thereof, and a float controlled sleeve slidably mounted upon the tube and manually adjustable to open position from the exterior of the tank and adapted to automatically open and close said tube when the liquid rises and falls above and below a predetermined point in the receptacle.
20. In a fuel reserve supply system, the combination with the manifold and carbureter of an internal combustion engine and the fuel supply tank therefor, a supply pipe connecting the tank and carbureter, and means for automatically closing the supply pipe when the liquid in the tank is reduced to a predetermined amount, said means being adjustable to permit the use of the reserve supply of fuel in the tank, and adapted to be automatically released from adjusted position when the supply of fuel in the tank is increased above the amount constituting the reserve supply.
21. In a fuel reserve supply system; the combination with the manifold and carbureter of an internal combustion engine and a vacuum gravity feed tank connected with said manifold and carbureter, a supply tank, a supply pipe connecting said supply tank with said vacuum gravity feed tank and means for automatically closing the supply pipe when the fuel in the supply tank is reduced to a predetermined amount, said means being adjustable manually from the exterior of the tank to permit the use of the reserve supply of fuel therein and adapted to be automatically released from adjusted position when the fuel in the supply tank is increased above the amount constituting the reserve supply.
22. In combination, a vacuum fuel feed system including a supply tank in which the fuel is submitted to atmospheric pressure, a device within the tank connected to
- said system adapted to prevent discharge of fuel from the tank when the fuel is reduced to a point below a predetermined level therein, said device being capable of adjustment to permit the remainder of the fuel to be withdrawn from the tank and adapted to automatically close the discharge outlet when a new supply of fuel has been placed in the tank and discharged to a point below said level and means for effecting adjustment of said device.
23. A liquid holding receptacle provided with a discharge passageway, an adjustable device adapted to prevent discharge of liquid through the passage when the liquid is reduced to a point below a predetermined level within the tank, said device being adapted to automatically close the passageway when a new supply of liquid has been placed in the tank and withdrawn to a point below said predetermined level and means manually operable from the exterior of the tank to effect adjustment of said device.
24. A liquid holding receptacle having a tube projecting therein provided with an inlet passageway adjacent its lower end, a float controlled member slidably mounted upon the tube arranged to automatically close said passageway when the liquid falls below a predetermined point within the tank whereby a reserve supply of fuel is maintained and means for manually setting said member to permit said reserve supply of fuel to flow through said tube, said setting means being automatically released when the tank is refilled to a point above said predetermined level.
25. In a liquid control device, a liquid holding receptacle having a discharge pipe leading from a point adjacent the bottom thereof, adjustable means controlled by the rise and fall of liquid in the receptacle adapted to automatically close said pipe when the liquid reaches a predetermined level within the receptacle to maintain a reserve supply therein and means for manually setting said adjustable means in position to permit said reserve supply to be withdrawn from the receptacle, said setting means being automatically released when a new supply of liquid is placed in the receptacle greater than said reserve supply.
26. In a liquid control device, a liquid holding receptacle, a suction tube projecting therein to a point adjacent the bottom of the receptacle and having an inlet opening at the lower end thereof, adapted to be constantly sealed by the liquid in the tank, adjustable means controlled by the rise and fall of the liquid in the tank adapted to automatically close said opening before the liquid is reduced to a level with said opening to maintain a reserve supply of liquid in the tank and means for setting said adjustable means in position to permit said

reserve supply to be withdrawn from the tank, said setting means being automatically released when a new supply of liquid is placed in the tank greater than said reserve supply.

27. A vacuum fuel feed system for internal combustion engines including a supply tank, a tube connected with said system and projecting into the tank to a point adjacent to the bottom thereof and having an inlet opening at its lower end adapted to be constantly sealed by the fuel in the tank and means within the tank adapted to automatically open and close said opening when the fuel rises and falls above a predetermined point within the tank.

28. A fuel control system comprising a fuel tank, a tube connected with the tank having a float controlled valve arranged to automatically close said tube when the fuel in the tank is reduced to a predetermined amount, and rotatably mounted means associated with said float controlled valve for lifting the same when closed.

29. A fuel control system for maintaining a reserve supply of fuel comprising a fuel tank, a tube connected with the tank, a float controlled valve arranged to automatically close said tube when the fuel in the tank is reduced to a predetermined amount, rotatably mounted means adjustable to effect the lifting of said valve from its seat and adapted to hold the same until the fuel in the tank is increased above said predetermined amount after which it is automatically released to permit the closing of the valve, and means adapted to return said rotatably mounted means to normal position when released.

40. 30. The combination with a vacuum fuel feed system of an internal combustion engine including the fuel tank, a receptacle

connected with said tank in position to be filled by gravity and from which the fuel is adapted to be drawn by said vacuum fuel feed system to be supplied to the carburetor of the engine, means adapted to automatically close said receptacle when the fuel in the tank is reduced to a predetermined amount, and means for setting said last mentioned means in position to maintain open communication between said receptacle and tank, said setting means being adapted to automatically return to normal position when the fuel in the tank is increased above a predetermined amount.

31. The combination with the vacuum fuel feed system of an internal combustion engine including the fuel supply tank, a receptacle within said tank having a fuel passageway communicating therewith, and manually adjustable means adapted to automatically close said passageway when the fuel in the tank reaches a predetermined level whereby the discharge of fuel from the tank is prevented.

32. The combination with the vacuum fuel feed system of an internal combustion engine including the fuel supply tank, a receptacle connected with said tank having a fuel passageway communicating therewith, means adapted to automatically close said passageway when the fuel in the tank reaches a predetermined level, and manually adjustable means connected with the receptacle for actuating said last mentioned means to open said passageway, said manually adjustable means being automatically released and returned to normal position when the fuel in the tank is increased above a predetermined point.

In testimony whereof I affix my signature.

FRANCIS JERDONE, JR.
